W. E. B. JORDAN.

HULLER RIB,

APPLICATION FILED JULY 18, 1921.

1,424,727.

Patented Aug. 1, 1922.

Sturtevant & Mason Attorneys

UNITED STATES PATENT OFFICE.

WALTER E. B. JORDAN, OF WILSON, NORTH CAROLINA.

HULLER RIB.

1,424,727.

Specification of Letters Patent. Patented Aug. 1, 1922.

Application filed July 18, 1921. Serial No. 485,552.

To all whom it may concern:

Be it known that I, WALTER E. B. JORDAN, a citizen of the United States, residing at Wilson, in the county of Wilson, State of North Carolina, have invented certain new and useful Improvements in Huller Ribs, of which the following is a description, reference being had to the accompanying drawing, and to the figures of reference marked thereon.

This invention relates to cotton gins, and more particularly to an improved form of huller rib adapted to prevent the choking of the cotton in the huller or outer breast of a double rib huller gin.

At the present time, considerable difficulty is experienced in ginning cotton—especially clean cotton, due to its tendency to string itself out from seed to seed and to be fed by the picker roller into the saws in such a manner that the severed end of the string furthest from the saws is thrown up against overlying knees or projections on the under side of the huller ribs. The cotton strings catch on these projections to such an extent as to cause a gradual accumulation of cotton at these projections and consequently prevents the cotton from being properly carried into the inner breast, resulting in the breakage of the roll and a considerable loss of time in ginning.

The present invention has for its object the provision of a huller rib constructed so as to eliminate or to minimize this objectionable choking.

A further object of this invention is to provide a standard rib such as described which can be quickly and readily substituted for the present type of huller ribs used in cotton gins.

These and other objects will in part be obvious and will in part be hereinafter more fully disclosed.

Referring more particularly to the accompanying drawings:

Figure 1 shows a sectional view of a standard double rib huller gin illustrating the design and location of my improved rib;

Fig. 2 is a side elevation of a single rib, and

Fig. 3 is a front view of the same.

In the drawings, the frame 1 of the cotton gin is arranged with the usual huller chamber 2, roll chamber 3, gin saw 4, brushes 5, and the picker roll 6. Adjacent the saws 4 in the spaces which separate the same in

the saw shaft are arranged the usual ribs 7 through which cotton from the roll box 8 is pulled to free it from seed prior to its passage on the saws to the lint removing brushes 9. All the foregoing is well known in the art.

The huller ribs 10 which form the subject matter of this invention are disposed as usual with their lower ends 11 secured as by screws or the like to the portion 12 of the frame 1.

Said huller rib 10 is provided with a central outwardly bowed portion 13 and an upper portion 14 which extends forwardly from said central portion. The under surface 15 of the upper portion is formed on a continuous curve which merges into the curved portion 16 at the upper end of the central portion referred to. This upper portion 14 has a narrow neck 20 adjacent its end, and said neck portion terminates in a relatively wide securing flange 18. Said flange is bent upwardly at 17 and is provided with an opening 21 through which suitable securing means is passed for securing the upper end of the huller rib to its supporting rail. The forward under surface 22 of the securing flange is curved upwardly to a point somewhat above the upper surface of the neck portion, and the ends 23 of the flange are also curved upwardly toward the upper face of the neck portion, and these ends are further curved so as to merge into the sides of the neck portion.

Clean cotton has a tendency to string out from seed to seed, and the outer ends of these strings when fed by the picker rolls 6 to the saws 7 are thrown upwardly by the action of the saws, and unless the huller rib is entirely free from shoulders, the cotton strings will catch on the shoulders and will accumulate. This is particularly true where there are any shoulders of any character at the upper end of the huller rib. The clinging cotton will bridge over to the outside wall of the roll box and prevent further feeding of the cotton to the inner rolls and cause its breaking.

In my improved form of huller rib where the securing flange is curved upwardly at its forward end and the rear ends are curved upwardly and curved so as to merge into the neck portion, all shoulders have been eliminated and this clogging and choking is avoided as the ends of the cotton strings

will slide over the smooth surfaces of the huller ribs into the saws.

It will be obvious that minor changes in the details of construction and the arrangement of the parts may be made without departing from the spirit of the invention as set forth in the appended claims.

Having thus described the invention, what I claim as new and desire to secure by Letters Patent, is:—

1. As an article of manufacture, a huller rib for a cotton gin comprising a central outwardly bowed portion, and an upper portion extending forwardly from said central portion and having its under surface continuously curved and merging into the curved surface of the central portion, said upper portion having a narrow neck adjacent its end and terminating in a relatively wide 20 securing flange, the ends of said flange ad-

jacent the neck being curved and merging into the sides of the neck.

2. As an article of manufacture, a huller rib for a cotton gin comprising a central outwardly bowed portion, and an upper portion 25 extending forward from said central portion and having its under surface continuously curved and merging into the curved surface of the central portion, said upper portion having a narrow neck adjacent its end and 30 terminating in a relatively wide securing flange, the forward under surface of said flange being curved upwardly to a point above the upper face of the neck portion and the ends of said flange adjacent the neck 35 portion being curved and merging into the sides of the neck portion.

In testimony whereof, I affix my signature.

WALTER E. B. JORDAN.
